J. C. STUGARD

FOLDABLE BRACKET

Filed Feb. 9, 1925

UNITED STATES PATENT OFFICE.

JAMES C. STUGARD, OF MUNCY, PENNSYLVANIA.

FOLDABLE BRACKET.

Application filed February 9, 1925. Serial No. 8,069.

To all whom it may concern:

Be it known that I, JAMES C. STUGARD, a citizen of the United States, residing at Muncy, in the county of Lycoming and 5 State of Pennsylvania, have invented certain new and useful Improvements in Foldable Brackets; and I do declare the following to be a full, clear, and exact description of the invention, such as will enable others 10 skilled in the art to which it appertains, to make and use the same.

My invention aims to provide an extremely simple and inexpensive, yet a very desirable form of bracket for supporting 15 any desired article, unique provision being made whereby an outer article-supporting member is connected with an inner stationary member in such a manner that the two may be rigidly connected for use but may be 20 quickly angled, so as to permit the outer member to fold compactly to an out-of-the-way position.

With the foregoing in view, the invention resides in the novel subject matter herein- 25 after described and claimed, the description being supplemented by the accompanying drawing.

Figure 1 is a side elevation of the improved bracket with the outer member 30 thereof shaped for use primarily as a support for a bucket or similar article.

Figure 2 is a top plan view.

Figure 3 is a longitudinal sectional view on line 3—3 of Fig. 2.

Figure 4 is a side elevation illustrating 35 the manner in which the outer member of the bracket may be folded.

Figure 5 is a plan view illustrating a different form of construction which is adapt- 40 ed for use as a bag holder.

Figure 6 is a side elevation partly in section, showing the device illustrated in Fig. 5.

Figure 7 is a perspective view of the bag 45 holding ring disclosed in Figs. 5 and 6.

In the drawing above briefly described, the numeral 1 designates a rigid, preferably horizontal arm which is adapted to be secured to an appropriate support, for which 50 purpose I have shown it provided with oppositely extending ears 2, through which appropriate fasteners 3 may be passed. The arm 1 is provided with an inner horizontal slot 4 and with an outer horizontal slot 5, an entrance throat 6 being provided from 55 the outer end of the latter to the upper

edge of said arm, while at the inner end of said slot 5, the lower side wall of the latter is formed with an offset, locking notch 7. An outer article-supporting member 8, 60 here shown in the form of a flared ring, is provided with parallel arms 9 which extend along opposite sides of the arm 1. A bolt or the like 10 passes through the arms 9 and the slot 4, and another bolt 11 which passes 65 through said arms 9, is receivable in the slot 5—6—7. When the bolt 10 is at the inner end of its slot 4, as seen in Fig. 3, the bolt 11 rests in the offset notch 7, so that accidental outward sliding of the support 8 is 70 prevented and consequently the bolt 11 can- not move upwardly through the throat 6, unless said support 8 is moved by hand in the required manner. This adapts the de- vice particularly for holding a pail 12 from 75 which a calf may be fed, and in practice, I have found that regardless of the calf's but- ting, the support 8 and the bucket will re- main in proper position.

When the device is not in use, the support 80 8 may be tilted upwardly to bring the bolt 11 in the horizontal slot 5, whereupon said support may be pulled outwardly until said bolt 11 may pass out of the throat 6. Then, the support may either be swung upwardly 85 as shown in Fig. 4, or by pulling it out- wardly until the bolt 11 clears the outer end of the arm 1, said support may be swung downwardly to an out-of-the-way position.

If it is desired to construct the device 90 primarily for supporting a sack, the sup- port 8 may be connected with the arm 1 in an inverted position as shown in Figs. 5 and 6, and a flared sack-clamping ring 13 may be provided, said ring having ears 14 95 straddling the arms 9 and pivoted upon the bolt 11.

By employing the novel construction shown and described, or a substantial equivalent thereof, a device is provided 100 which is exceptionally simple and inex- pensive, yet is very desirable, and may be con- structed for application to a wide variety of uses. On account of the advantages de- rived from the details shown, they are by 105 preference followed, but within the scope of the invention as claimed, modifications may of course be made.

I claim:

1. A foldable bracket comprising an in- 110 ner stationary member having an inner horizontal slot and an outer horizontal slot,

the outer end of said outer slot having an inlet throat which opens through the upper edge of said member, an outer article-supporting member at the outer end of the inner member, said outer member having an arm disposed at one side of said inner member a fastener passing through said arm and the inner slot of said inner member, and another fastener passing through 10 the arm and the outer slot of said inner member, the first named fastener constituting a pivot for the outer member when the latter is shifted outwardly and swung to move the second named fastener through 15 the throat of said outer slot, the lower side wall of said outer slot being provided at its inner end with an offset notch to normally receive and form a lock for second named fastener, whereby accidental outward sliding movement of said outer article 20 supporting member is prevented.

2. A foldable bracket comprising an inner stationary member having an inner horizontal slot and an outer horizontal slot,

the outer end of said outer slot having an 25 inlet throat which opens through the upper edge of said member, and the inner end of said outer slot having an offset locking notch, an outer article-supporting member at the outer end of the inner member, said 30 outer member being in the form of a ring having a pair of parallel arms straddling said inner member and extending across the inner and outer slots thereof, an inner fastener passing through said arms and 35 said inner slot, and an outer fastener passing through said arms and the outer slot, and adapted to engage said locking notch to prevent accidental outward movement of the outer supporting member, said outer 40 fastener being released from said notch and movable through said throat, when the supporting member is swung upwardly about said inner fastener, and shifted outwardly.

In testimony whereof I have hereunto 45 affixed my signature.

JAMES C. STUGARD.
